REVOLVING SHELVING FOR REFRIGERATORS AND THE LIKE

William E. Wilson, Los Angeles, Calif.

Application May 18, 1944, Serial No. 536,189

3 Claims. (Cl. 312—183)

The invention relates to shelving for refrigerators and the like, and has for an object to provide a shelving made up of independent sections or units, which are grouped about a common axis and turnable to position a selected section or unit in line with the front opening of a refrigerator or like cabinet for ease and convenience in the removal and replacement of articles supported on the individual shelves of such section or unit.

Another object of the invention is the provision of a shelving of this character, wherein the removal of the several shelving sections or units enables the easy cleaning of the interior of a refrigerator or the like, as well as the shelving, with ease and dispatch.

With these and other objects in view, the invention consists in the features of construction, combination and arrangement of parts as will be hereinafter more fully described, illustrated in the accompanying drawing, which shows the preferred embodiment of the invention, and pointed out in the claims hereunto appended.

In the accompanying drawing:

Figure 1 is a horizontal sectional view through the refrigerator constructed in accordance with the invention.

Figure 2 is a fragmentary sectional view taken on the line 2—2 of Figure 1 looking in the direction of the arrows.

Figure 3 is a sectional view taken on the line 3—3 of Figure 2 looking in the direction of the arrows.

Figure 4 is a fragmentary side view, partly broken away, of one shelving unit.

Figure 5 is an enlarged horizontal sectional view through the rotary axis of the assembled shelving units when set up within the refrigerator.

Similar reference characters indicate corresponding parts throughout the several views in the drawing.

Referring to the drawing in detail, A designates generally a portion of a refrigerator constructed in accordance with the invention, and comprises a casing, a portion thereof being denoted at 10, having an inner lining wall 11, provided with a circulatory cooling space 12, intersected by an entrance 13 at the front of the casing. This entrance 13 matches a doorway normally closed by a horizontally swinging door 14, hingedly supported, and latched in a closed position by a hand released latch 15.

At opposite sides of the entrance 13 and accessible therethrough are shelved compartments 16 for the storage of bottled goods or other merchandise.

Within the cooling space 12 is a sectional revolving shelving set-up, which involves a plurality of sector-shaped removable shelf units 17, each formed with spaced superposed shelves 18, supported upon a shaft section 18' of sector-shape in cross section which tapers upwardly, and which at its upper end is provided with a break-joint 19 adapted to break in only one direction, as shown in Figure 4. This segment 18' is adapted to interfit with the remaining segments of the other units, as is clearly shown in Figure 5 of the drawing, for the rotatable socketing at 20 and 21, respectively, in the top and bottom of the casing of the refrigerator A, so that the shelving units 17 may be turned in mass, to have any area of their shelves 18 accessible through the entrance 13 for the placement or removal of articles in and from the refrigerator A.

Each shelf section or unit 17 is readily and easily removable from the space 12, by first lifting a selected shelf section or unit sufficiently to free the lower end of its shaft segment 18' from the lower socket 20, then pulling the lower part of the shaft segment forward to break the joint 19, and thereafter lowering the shelf section or unit to free the upper part of the shaft segment from the upper socket. A shelf section or unit 17 is of a size to permit its removal through the entrance 13, when the door 14 has been swung to full open position. The removal of the several shelf sections or units 17 permits of easy cleaning of the interior of a refrigerator A. The individual shelves 18 are braced and reinforced at 22 and 23, and the lower end of each shaft segment 18' is preferably equipped with anti-friction bearings 24, of any suitable kind.

It is, of course, understood that such changes, variations and modifications may be made in the invention, as fall properly within the scope of the appended claims, without departing from the spirit of the invention or sacrificing any of its advantages.

What is claimed is:

- 45 1. A cabinet of the character described, comprising a casing having upper and lower sockets, a series of sector-shaped shelf sections having sector-shaped shaft sections at their inner ends forming a shaft rotatably mounted in said sockets.
2. A cabinet of the character described, comprising a casing having upper and lower sockets, a series of sector-shaped shelf sections having sector-shaped shaft sections at their inner ends forming a shaft rotatably mounted in said sockets, and each shaft section having a break joint

whereby either end of the assembled sections is adapted to swing outwardly.

3. A cabinet of the character described, comprising a closed casing having a socket in its top wall and a socket in the bottom directly below the upper socket, a series of sector-shaped shelf sections having sector-shaped shaft sections at their inner ends forming a shaft adapted to ro-

tate in said sockets, and each shaft section having a break joint adjacent its upper end whereby the lower end of any shaft section is adapted to be swung outwardly after the shaft section has been lifted to withdraw its lower end from the bottom socket.

WILLIAM E. WILSON.
